ATTORNEYS.

UNITED STATES PATENT OFFICE.

THOMAS M. HILLIARD, OF NEW YORK, N. Y., ASSIGNOR OF ONE-HALF TO
HENRY A. PARR, OF SAME PLACE.

DESIGN FOR A GUARD FOR KEYS.

SPECIFICATION forming part of Design No. 27,911, dated November 30, 1897.

Application filed September 3, 1897. Serial No. 650,536. Term of patent 7 years.

To all whom it may concern:

Be it known that I, THOMAS M. HILLIARD, a citizen of the United States, residing at New York city, in the county and State of New York, have invented and produced a new and original Design for a Guard for Keys, of which the following is a specification, reference being had to the accompanying drawing, forming a part thereof, in which the figure is a

5 perspective view of a key-guard embodying the features of my design, together with a belt connected with the guard.

The design relates especially to a sheath or guard for a bunch of keys, having for its object to prevent keys being worn upon the person from marring any article or house-trim-
15 ming with which the said keys might otherwise be brought in contact.

The leading feature of the design consists in the sheath A, which is tubular, the side lines 20 whereof are inclined in opposite directions, diverging at the bottom and converging at the top, imparting to said sheath more or less of a bell shape. The upper end portion of the sheath receives an end of a belt, the belt 25 being of a character to extend around a person.

I claim—

The design for the guard for keys herein shown and described.

THOMAS M. HILLIARD.

Witnesses:

H. A. PARR,
ROLAND L. JANES.
